C. L. LEONARD

VEGETABLE SLICER

Filed Aug. 17, 1920

Inventor

C. L. LEONARD

By Monroe E. Miller

Attorney

UNITED STATES PATENT OFFICE.

CASWELL L. LEONARD, OF CORINTH, MISSISSIPPI.

VEGETABLE SLICER.

Application filed August 17, 1920. Serial No. 404,182.

To all whom it may concern:

Be it known that I, CASWELL LEE LEONARD, a citizen of the United States, residing at Corinth, in the county of Alcorn and State 5 of Mississippi, have invented certain new and useful Improvements in Vegetable Slicers, of which the following is a specification, reference being had therein to the accompanying drawing.

10 The present invention relates to vegetable slicers, and aims to provide a practical and convenient device of that character of novel and improved construction, which is also simple and inexpensive to manufacture, as 15 well as being thoroughly efficient in use.

Another object is the provision of such a device having novel means for supporting the vegetable holder from the top of a table, or the like.

20 A further object is the provision of a rotatable disk having cutters movable past one end of the holder for slicing the object disposed in said holder, and novel means for mounting said disk for rotation and guiding 25 the edge thereof, to maintain the disk in proper position and permit of adjustment thereof closer to or farther away from the holder.

With the foregoing and other objects in 30 view, which will be apparent as the description proceeds, the invention resides in the construction and arrangement of parts hereinafter described and claimed, it being understood that changes can be made within 35 the scope of what is claimed without departing from the spirit of the invention.

The invention is illustrated in the accompanying drawing, wherein:—

40 Figure 1 is a rear view of the improved device.

Fig. 2 is a plan view thereof, portions being shown in section.

Fig. 3 is an elevation of the adjustable guide for the edge of the cutter disk.

45 Fig. 4 is an elevation of the disk bearing, portions being shown in section.

The holder 6 in which the vegetable or other object to be sliced is placed, is of 50 trough or channel shape, and is disposed horizontally. Said holder is supported by a pair of legs 7 and 8 secured to the opposite sides of the holder between the ends thereof. The leg 7 has a foot 9 extending at an angle away from the leg 8, to seat on the top 11 of 55 a table or similar support, and said foot 9 has a hook 10 to engage around and under

the edge portion of the table with the leg 8 adjacent to another edge of the table top, as seen in Fig. 2. The leg 8 has a foot 12 extending at an angle away from the leg 7 to 60 seat on the table top 11, and a clamp 13 is slipped over the corresponding edge portion of the table and has a clamping screw 14 for clamping the foot 12 down on the table top 11, thereby also holding the foot 9 and hook 65 10 firmly in engagement with the table top, to rigidly support the holder 6.

A sheet metal cutter disk 15 is disposed in a vertical plane transversely of the holder 6, with that portion of the disk at one side 70 of the center thereof extending across the inner end of the holder 6. The disk 15 has several radial slots 16 with the ends 17 extending at an angle, and forming cutter blades 18, which blades are bent or struck 75 at an angle rearwardly from the disk 15 and sharpened, whereby the disk 15 is being rotated (counter clock-wise as seen in Fig. 1) will cause the blades 18 to move downwardly across the inner end of the holder 80 6 for slicing the object, and the slices of material pass through the slots 16 to fall onto the table top 11 or a dish or receptacle supported thereon underneath the cutter disk 15 and inner end of the holder 6. The 85 cutter blades 18 can be bent toward or away from the plane of the disk, for reducing or increasing, respectively, the thicknesses of the slices, as may be desired.

The cutter disk is mounted for rotation 90 from one side of the holder 6, and, for this purpose, a longitudinal horizontal pintle 19, comprising a bolt as shown, extends through the center of the disk, for supporting same for rotation, and a pulley wheel 20 is preferably secured by rivets or otherwise to the central portion of the disk 15 at the forward side thereof, and serves as a hub for the disk mounted on the pintle or bolt 19. The 95 pintle or bolt 19 extends through a bearing 21 disposed at one side of the holder 6 at the forward or inner end thereof in a horizontal longitudinal position, and said bearing has a plate 22 resting against the corresponding side of the holder 6 and secured thereto by means of bolts or screws 23, said plate having horizontal longitudinal slots 24 for the bolts 23, to enable the bearing 21 to be adjusted longitudinally, for adjusting the cutter disk 15 closer to or farther away from the holder 6, according to the amount that the cutter blades 18 are bent from the plane 100 105 110

of the disk 15. The bearing 21 projects beyond the plate 22 to abut the disk 15, and thus enable the disk to rotate freely.

In order to guide the edge of the cutter disk and maintain the disk in proper position across the end of the holder 6, a longitudinal plate 25 is disposed against that side of the holder 6 opposite to the bearing 21 at the inner or forward end of the holder, and has a hooked or bent portion 26 forming a notch in which the edge portion of the disk 15 moves, whereby to prevent the disk from being sprung away from the holder 6 by the pressure of the object against the disk when slicing, the object being pushed against the disk by the hand to facilitate slicing. The plate 25 is secured to the holder 6 by means of bolts or screws 27 and said plate has a longitudinal slot 28¹ for said bolts, so that the plate 25 can be adjusted to correspond with the adjustment of the plate 22 and bearing 21.

The disk 15 is rotated conveniently by means of a crank handle 28 extending forwardly from the disk near the edges thereof, and detachably secured to the disk by means of a screw 29 extending forwardly through

the disk and screw-threaded into the handle.

When it is desired to rotate the disk 15 by an electric motor, or the like, the handle 28 can be moved by removing the screw 29, and the disk can then be connected to the motor by means of a belt passing around the pulley wheel 20, thereby saving labor when considerable amount of slicing is to be done.

Having thus described the invention, what is claimed as new is:—

A slicer comprising a channel-shaped holder, a cutter disk having cutter blades movable across one end of the holder, a bearing at one side of the holder supporting said disk for rotation, a guide member at the opposite side of the holder engaging the edge of the disk, and clamping members carried by the opposite sides of the holder, said bearing and guide member having slotted portions engaging said clamping members for the longitudinal adjustment of said bearing, disk and guide member when the clamping members are loosened.

In testimony whereof I hereunto affix my signature.

CASWELL L. LEONARD.
